UNITED STATES PATENT OFFICE.

HARRY SCHREIBMAN AND LOUIS GOLDBERG, OF BROOKLYN, NEW YORK.

DESIGN FOR A PANEL PLATE OR GRILLE FOR A LIGHTING FIXTURE OR LIKE ARTICLE.

Application filed February 9, 1928. Serial No. 25,336. Term of patent 3½ years.

To all whom it may concern:

Be it known that HARRY SCHREIBMAN and LOUIS GOLDBERG, citizens of the United States, and residents of New York city, borough of Brooklyn, in the county of Kings and State of New York, have invented a new, original, and ornamental Design for a Panel Plate or Grille for a Lighting Fixture or Like Article, of which the following is a specification, reference being had to the accompanying drawing, forming part thereof, in which—

Figs. 1 and 2 are front and side elevational views of a panel plate or grille for a lighting fixture embodying the invention.

We claim:

The ornamental design for a panel plate or grille for a lighting fixture or like article as shown.

Dated, New York city, February 1, 1928.

HARRY SCHREIBMAN.
LOUIS GOLDBERG.
